(57) **CLAIM**

The ornamental design for a virtual reality viewer, as shown and described.

DESCRIPTION

FIG. 1 is a front-top perspective view of a virtual reality viewer;

FIG. 2 is a front-top perspective view of a virtual reality viewer shown in FIG. 1 with a front cover in an opened configuration;

FIG. 3 is a bottom-rear perspective view of a virtual reality viewer shown in FIG. 1;

FIG. 4 is a rear-top perspective view of a virtual reality viewer shown in FIG. 1;

FIG. 5 is a top view of a virtual reality viewer shown in FIG. 1;

FIG. 6 is a bottom view of a virtual reality viewer shown in FIG. 1;

FIG. 7 is a front view of a virtual reality viewer shown in FIG. 1;

FIG. 8 is a rear view of a virtual reality viewer shown in FIG. 1;

FIG. 9 is a right-side view of a virtual reality viewer shown in FIG. 1;

FIG. 10 is a left-side view of a virtual reality viewer shown in FIG. 1;

FIG. 11 is a front perspective view of left and right adjustable lens fixtures with lenses of the virtual reality viewer shown in FIG. 1;

FIG. 12 is a front-bottom perspective view of the right lens fixture in a partially unfolded configuration for the virtual reality viewer shown in FIG. 1;

FIG. 13 is a front perspective view the lens of the right lens fixture of the virtual reality viewer shown in FIG. 11;

FIG. 14 is a front perspective view of a virtual reality viewer shown in FIG. 1; and,

FIG. 15 is a view of a die-cut pattern portion and the left and right adjustable lens fixtures of the virtual reality viewer shown in FIG. 1 as shown in an unfolded configuration.

Any broken lines in the drawings represent portions of the virtual reality viewer or represent environment that form no part of the claimed design.

1 Claim, 8 Drawing Sheets
